ELECTRO HYDRAULIC SERVO DEVICE

Martin P. Wolpin, Tonawanda, and Johannes G. Goerner, Snyder, N.Y., assignors, by mesne assignments, to Bell Aerospace Corporation, Wheatfield, N.Y., a corporation of Delaware

Filed Apr. 12, 1957, Ser. No. 652,608

2 Claims. (Cl. 137—82)

This invention relates in general to servo mechanisms, and in particular to electro hydraulic servo valves, such as shown in copending application, Serial No. 511,088 filed May 25, 1955, by Martin P. Wolpin, et al. Furthermore, this invention comprises improvements over mechanisms as shown for example in U.S. Patents 2,655,939; 2,655,940; 2,625,136; 2,767,689; and British Patent 712,329 of 1954.

An object of the present invention is to provide a valve of the aforesaid type in which the electrical parts of the valve are sealed off in improved manner from the fluid containing chambers thereof.

Another object is to provide an improved valve as aforesaid wherein the armature is mounted and stabilized in its fulcruming operation in improved manner.

Another object is to provide an improved device as aforesaid wherein the armature element is stabilized against acceleration forces.

Another object of the invention is to provide an improved valve as aforesaid which may be economically made by standard type production methods.

Another object is to provide a valve as aforesaid having relatively few parts.

Other objects and advantages of the invention will be apparent from the following specification wherein one form of the invention is shown in the accompanying drawings, of which:

FIG. 1 is a vertical sectional view, somewhat in diagram, of one form of the device of the invention; and

FIG. 2 is a sectional view taken on line II—II of FIG. 1.

As shown in the drawing, one form of the device of the invention may be employed in conjunction with an hydraulic valve mechanism shown to comprise a body 15 having therewithin a valve spool 25 and oil passageways (not shown) as disclosed for example in FIG. 1 of copending U.S. patent application Serial No. 511,088 filed May 25, 1955, by Martin P. Wolpin et al.; the fluid passageways exiting from the valve body 15 as indicated at 16, 18, 20, 22, 30, 32 and 34. As in the prior application referred to, an actuator comprising cylinder 24, piston 26, and connecting rod 28, or the like, may be operatively coupled to the fluid conduits 20, 22 so that the latter open into the cylinder 24 at opposite sides of the piston. The port 16 constitutes the pressured fluid inlet of the valve mechanism, while the port 18 constitutes the return line; and thus it will be understood that shifting of the valve spool 25 within the body 15, as controlled by the electro-magnetic component of the device as will be explained hereinafter, will cause the actuator 28 to be displaced in accord with the purpose of the mechanism.

As in the case of the copending patent application, the fluid passageways 30, 32 normally supply oil under equal pressures from chambers at opposite ends of the valve spool 25, to corresponding opposed nozzles 40, 42 mounted as in a body block 44 and arranged to jet oil against opposite sides of a flattened end portion 46 of the armature 50 of the electromagnetic component of the device. The armature end portion 46 is disposed within an oil chamber 52 formed in body block 44, and chamber 52 communicates with port 34 which leads to the oil return conduit 18. The

2

armature end portion 46 is normally centered between the nozzles 40, 42 and is slightly spaced equally in relation therfrom, whereby constant flows of oil may pass through the nozzles 40, 42 from the chambers at opposite ends of the valve spool against the armature part 46 and thence through the return conduit. However, any displacement of the armature part relative to the nozzles 40, 42 will differentially throttle the latter, and thereby upset the previous pressure equilibrium at opposite ends of the valve spool 25. This will cause the valve spool to shift with consequent adjustment of the valve action controlling flow of oil from the inlet 16 through actuator parts 20, 22; thereby energizing the actuator 28 consonant with the degree of deflection of the armature part 46 from its normal centralized position.

To provide for such operation of the armature it is resiliently mounted relative to the body portions 44, 54; as shown in FIG. 1 such resilient mounting may be provided by means of a hat-shaped housing 56 formed of spring material mounted in fluid sealed relation to and embracing the midportion of the armature bar 50; the bottom skirt portion of the housing 56 being welded or otherwise suitably fixed in fluid-sealed relation as indicated at 58 to a base plate 60 which is bolted as indicated at 62 to the body block 44. Thus, the joints between the housing 56 and the armature 50 and the base plate 60 are of fluid-pressure-sealed type, and a pressure seal as indicated at 64 is preferably employed to seal the joint between the plate 60 and the body member 44. As shown in FIG. 1, the armature device is conveniently constructed of an upper section 50 and a lower section 65 carrying the flat end portion 46; the sections 50, 65 being telescopically interfitted to provide the unitary assembly.

To cause the armature to rock upon the housing 56 as its fulcrum, electro-magnet coils 68, 70 are mounted within an enclosing housing 72 at opposite sides of the armature, and are arranged to be differentially energized in response to any control or error or other input signal, as is well understood in the art. Permanent magnets as indicated at 74, 76 may also be employed at opposite sides of the armature for normally biasing the armature to centralized position. Thus, rocking of the armature for differential throttling of the nozzles 40, 42 will be accomplished in response to a signal and to a degree commensurate with the strength of the signal to the coils 68, 70, as they may overcome the balanced forces of the permanent magnets and as controlled by the spring rate of the resilient housing 56. Thus, the housing 56 functions simultaneously to normally spring-bias the armature towards nozzle-centered position and controls oscillations thereof and returns it to central position upon lapse of any biasing signal; while at the same time it fluid seals the coils 68, 70 from contamination by oil from the nozzle chamber of the mechanism.

It is another particular feature of the present invention that the upper end of the support tube 56 is stabilized in a novel manner, such as by straps 80—80 extending diametrically from the upper end of the tube 56 into fixed connections with opposite sides of the base member 82 which may be either integral with the base member 44 or rigidly connected thereto to assist in mounting the components of the mechanism. The straps 80—80 extend in the plane of oscillation of the armature 50—65, and thus they firmly maintain the center of oscillation of the armature always at the same elevation; that is, in line with the straps 80—80. Hence, in spite of varying net magnetic and hydraulic forces on the armature, the armature always pivots about the same center; and thus it is practicable to construct the device to accept lateral forces with uniformly predictable results. None the less, because the straps 80—80 are flexible they provide no interference with oscillation of the armature.

What is claimed is:

1. A pilot valve for control of a pair of oppositely arranged fluid pressure nozzles, said valve comprising a body, a resilient collar carried by said body in fluid-sealed relation therewith, a flapper valve assembly comprising an armature extending through and carried by said collar in fluid-sealed relation therewith and formed with a tip portion disposed between said nozzles for oscillating movement relative thereto, restraint means extending from said body to said collar to stabilize the latter against lateral displacement and thereby maintain a fixed level of fulcruming of said armature relative to said body, and motor means operable to impose biasing forces upon said armature whereby operation of said motor means will cause the flapper valve assembly to rock while elastically deforming said collar. 15

2. A pilot valve for control of a servo valve comprising a body, oppositely arranged fluid pressure nozzles carried by said body, a resilient collar carried by said body in fluid-sealed relation therewith adjacent one end of said collar, an armature assembly formed of magnetic-responsive material extending through and carried by the opposite end of said collar in fluid-sealed relation therewith and formed with a flat tip portion disposed between said nozzles for oscillating movement relative thereto, flexible strap means extending from said body in the plane of oscillation of said armature and connected to said collar 20

5 at a point spaced from said one end thereof to stabilize a portion thereof against lateral displacement and to thereby establish a fixed level of fulcruming of said armature relative to said body, said armature extending outwardly from said collar and disposed between the poles of an electromagnet, whereby variable signals received by said electromagnet will cause the armature assembly to rock within said collar for corresponding variable throttling of said nozzles.
